UNITED STATES PATENT OFFICE.

JAMES K. SCHENCK, OF SEATTLE, WASHINGTON.

DISAPPEARING WINDOW-SCREEN.

1,314,221.

Specification of Letters Patent. Patented Aug. 26, 1919.

Application filed July 27, 1917, Serial No. 183,991. Renewed December 27, 1918. Serial No. 268,497.

To all whom it may concern:

Be it known that I, JAMES K. SCHENCK, a citizen of the United States, residing at Seattle, in the county of King and State of 5 Washington, have invented a new and useful Improvement in Disappearing Window-Screens, of which the following is a specification.

This invention relates to improvements 10 in disappearing window screens, and the object of this improvement is to simplify the details of construction and make the screen more efficient in operation and more easy to install on a window.

15 This invention is in the nature of an improvement on the disappearing window screen disclosed in the co-pending application of Harold B. Schenck, Serial Number 90985, filed April 10, 1916, and is directed to 20 improve a means for securing the top edge of the screen to the bottom of the window sash; to an improved form of guideways for the edges of the screen and the method of securing such guideways to the window casing; 25 and to improvements in the form of the roller housing, and the means for securing such housing to the window casing.

In the accompanying drawings, Figure 1 is a view in elevation of the lower portion 30 of a window upon which this screen is installed; Fig. 2 is a sectional view of the same on broken line 2, 2, of Fig. 1; Fig. 3 is a view in cross section substantially on broken line 3, 3 of Fig. 1, showing the 35 method of fastening the housing to the casing and showing the screen roller broken away; Figs. 4 and 5 are enlarged views in perspective illustrating the details of the members that are used for connecting the 40 screen to the window sash; Fig. 6 is a view in perspective showing the method of securing the screen to the cross bar; Fig. 7 is a fragmentary view in perspective illustrating the telescopic guide members and the means 45 of securing such guide members to the window casing, and Fig. 8 is a fragmentary view in perspective showing an alternative manner of connecting the screen to the top cross bar.

50 This screen is herein shown and described as applied to the lower sash only of a window, but it will be understood that the same may be applied to the upper sash of a window without any substantial change of form.

55 Referring to the drawings throughout, in

which like reference numerals indicate like parts, the numeral 9 indicates a window frame that is provided with a window sill 10 and with lower and upper sashes 11 and 12 respectively that are adapted to move 60 vertically between stops 13, 14 and 15.

This invention consists of a screen 16 that is secured at one end to a roller 17 and adapted to be wound thereon when it is not 65 in use.

The roller 17 is provided with an internally disposed spring 18 and is constructed in substantially the same manner as an ordinary curtain roller, except that it is made heavier and stronger and is of large enough 70 diameter so that it will not damage or deform the screen as it is wound thereon.

The roller is disposed within a housing 20 that is preferably of arcuate cross sectional shape, as shown in Fig. 2, and large 75 enough to contain the screen when it is wound up.

The housing 20 is preferably formed of sheet metal and has sheet metal end members 21, one of which has a square hole 80 22 for the reception of a flattened stud on the end of the spring roller and the other of which is provided with a hole through which a screw 23 may be inserted into the roller. The roller may be easily removed 85 from the housing by first taking out the screw 23.

The housing 20 is preferably secured to the window casing 9 by two rods 24 that are articulated with a lever arm 25 on opposite 90 sides of a pivot 26 by which such lever arm is secured to the bottom of the housing, and which extend outwardly in opposite directions through the end plates on the opposite ends of the housing, so that when the 95 lever arm 25, as seen in Fig. 3, is turned to the left the sharpened ends 27 of the bars will be withdrawn into the housing and when the lever arm 25 is turned to the right, such sharpened ends will be projected outwardly 100 through the ends of the housing and forced into the sides of the window casing, thus securely fastening the housing 20 to the casing 9.

If desired, the method of fastening described above may be dispensed with and the housing may be secured to the window sill by screws or nails 60, as indicated by dotted lines in Fig. 3.

The edge of the screen opposite the roller 110

is fastened within a sheet metal cross bar that is formed of three overlapping parts 28, 29 and 30, as shown in Fig. 6, the end of the screen being bent over the edge of the part 29 and securely crimped between the parts 29 and 30.

The end of the screen is secured to the bottom of the sash by two angular members 31 and 32 that are adapted to have one portion hook under the part 28 and are provided in the other portion with keyhole slots 33 that fit over and are secured upon studs 34 on a plate 35 on the bottom of the sash.

The part 28 is pressed tightly against the screen for the greater portion of its length, but is left free from the screen for a short distance near each end so that the members 31 and 32 may be inserted thereunder.

The portions of the members 31 and 32 that hook under the part 28 of the metal bar are provided with elongated slots 36 and the part 28 is indented by stamping as at 37 to form studs or protruding portions that project into the slot 36 to prevent the members 31 and 32 from becoming detached, and at the same time permit such members to move lengthwise of the cross bar.

The members 31 and 32 are easily secured to the window sash by slipping the larger portions of the keyhole slots 33 over the heads of the studs 34 and then moving such members sidewise until the studs 34 are within the narrower portions of the slots 33.

When the screen is secured to the window the bar along the top edge of the screen is held closely against the outside of the bottom rail of the sash, as shown in Fig. 2.

When the screen is detached from the sash the members 31 and 32 will engage with the housing 20 and prevent the screen from unwinding.

The members 31 and 32 may be removed from the screen bar by springing the part 28 outwardly.

45 38 are U shaped guides that are secured to the window stop 14 by means of keyhole shaped slots 39 in the edge of the guides that may be placed over and secured on nails or tacks 40 that are driven into the window stop.

The guides are adapted for the reception of the edges of the screen and are preferably made in two parts and telescoped together, see Fig. 7, so that they may be adjusted to windows of a different size without being cut off.

At the bottom of the guides 38, the outer side thereof may be cut off and secured to the housing 20 as shown at 38¹ and the inner side thereof may extend downward into close proximity to the window sill, as shown at 38², see Fig. 2.

41 is a strip preferably of fiber board that is secured to the lower side of the top sash

in such a position that it projects outwardly 65 into close proximity to the glass pane of the bottom sash to prevent the entrance of insects when the bottom sash is raised.

This screen is easy to install on a window and may be quickly and easily unfastened 70 from the sash when it is not needed.

When the screen is not in use it may be left on the window within the housing 20 by which it is protected, or if desired, the housing and screen may both be removed 75 from the window.

When the window is closed the screen is entirely out of sight and out of the way, thus permitting a clear and unobstructed view through the window, and leaving the 80 outer surface of the window free of access for cleaning.

Fig. 8 illustrates an alternative manner of securing the screen to the top cross bar. In this figure the cross bar is formed in the 85 shape of a letter U, with one edge bent inwardly, as indicated at 42, and the top edge of the screen is doubled over and a strip or key 43 is inserted between the doubled over portion of the screen and the bent portion 90 42 of the bar, in the manner shown to secure the screen to the cross bar.

When the screen is secured to the cross bar in this manner, it may be easily removed by taking out the key 43.

It is obvious that changes in the form of the various parts herein disclosed may be resorted to within the scope of the following claims.

What I claim and desire to protect by Letters Patent is:

1. The combination with a window frame having a vertically movable sash of a housing secured to said frame, a spring roller rotatably mounted in said housing, a screen having one end secured to said roller, a cross bar on the opposite end of said screen, angular plates secured to said cross bar and movable lengthwise thereof said plates having keyhole shaped slots therein, downwardly projecting studs on the bottom of said window sash to engage within said keyhole shaped slots and secure said screen to said sash whereby when said sash is in a closed position said screen will be wound upon said roller and when said sash is in an open position said screen will be stretched across the opening in said window, and guideways secured to said frame for the reception of the edges of said screen.

2. The combination with a window frame having a vertically movable sash of a spring roller rotatably secured to said frame, a screen having one end secured to said roller, a cross bar secured to other end of said screen, downwardly projecting studs secured to the bottom rail of said window sash and angular plates secured to said cross

bar and movable lengthwise thereof, said plates having keyhole shaped slots adapted to be placed over and engage with said studs removably to secure the top edge of 5 said screen to said sash.

3. Combination with a window frame having a vertically movable sash of a housing disposed near the lower portion of said frame, a lever arm pivoted to said housing, 10 bars extending lengthwise of said housing and projecting outwardly through the ends thereof, the inner ends of said bars being articulated with said lever arm on opposite sides of its pivot and the outer ends of said 15 bars being pointed, whereby they may be forced into said window casing by turning said lever arm to secure said housing to said casing, a spring roller mounted in said housing, a screen secured at one end to said 20 roller and adapted to wind thereon, and means for securing the other end of said screen to said sash.

4. The combination with a window casing having a vertically movable sash of a 25 housing, means for securing said housing to said frame, a spring roller mounted in said housing, a screen secured at one end to said roller, a cross bar secured to the opposite end of said screen, plates secured to the bottom 30 of the lower rail of said window sash, studs projecting downwardly from said plates, and angular members secured to said cross bar and movable lengthwise thereof, said angular members having keyhole shaped

slots adapted to fit over said studs to secure 35 the top edge of said screen to said sash.

5. The combination with a window frame having a vertically movable sash, of a spring roller rotatably secured to said frame a screen having one end secured to said roller 40 and adapted to wind thereon, a cross bar on the opposite end of said screen, said cross bar being formed of a plurality of overlapping sections of sheet metal that are crimped securely to the end of said screen, 45 one of said overlapping sections being slightly spaced from said screen, plates adapted to be secured to the edge of said sash, said plates having downwardly directed studs, and L shaped members having 50 keyhole shaped slots in one portion thereof that are adapted to fit over and be secured on said studs, the other portions of said plates being adapted to be inserted under the spaced portions of said cross bar section, 55 and having elongated slots whereby the metal of said cross bar section may be punched into said slots to secure said L shaped members to said cross bar and admit of a limited movement lengthwise 60 thereof.

Signed by me at Seattle, Washington,
this 28 day of May, 1917.

JAMES K. SCHENCK.
